UNITED STATES PATENT OFFICE.

FRANK W. RICHEY, OF CHICAGO, ILLINOIS.

STAPLE-FASTENER FOR WOODEN VESSELS OR BOXES.

SPECIFICATION forming part of Letters Patent No. 527,184, dated October 9, 1894.

Application filed November 27, 1893. Serial No. 492,177. (No model.)

To all whom it may concern:

Be it known that I, FRANK W. RICHEY, a citizen of the United States, residing at Chicago, in the county of Cook and State of Illinois, have invented certain new and useful Improvements in Staple-Fasteners for Wooden Vessels or Boxes, of which the following is a specification, reference being had therein to the accompanying drawings.

10 This invention relates to staple fasteners for wooden vessels and boxes.

The main and primary object of the present invention is to provide a cheap and suitable device of this character that can be readily applied to wooden vessels and boxes by anyone without special instructions, and to this end the invention therefore contemplates a simple and useful device of this character providing effective means for securing covers 15 to packing boxes, tobacco pails, jelly boxes, lard, butter, candy and other pails, and the like.

With these and other objects in view which will readily appear as the nature of the invention is better understood, the same consists in the novel construction, combination and arrangement of parts hereinafter more fully described, illustrated and claimed.

In the accompanying drawings—Figure 1 is 20 a side elevation of a staple fastener constructed in accordance with this invention. Fig. 2 is an end view thereof. Fig. 3 is a detail cross sectional view of the flexible main body portion of the fastener, the lines X—X and F—F indicating the difference in the thickness and width of the wire comprising the body portion. Fig. 4 is a detail plan view showing a section or length of wire illustrating the manner of manufacturing the herein 25 described fastener. Fig. 5 is a detail view illustrating one of the improved staple fasteners as applied to a box preparatory to driving the point-shanks. Fig. 6 is a similar view showing one of the fasteners after having 30 been applied to a package showing the angle of the point shanks as they appear when driven into the wood.

Referring to the accompanying drawings, A designates the main straight body portion of 35 a staple fastener adapted to be used at the corner of a box or package for the purpose of securing the cover thereto, and said body portion

A, is formed out of a suitable length of flexible wire rolled into half oval shape to provide the fastener with a flattened side a, which 55 clamps flat onto the box or package and the cover which it secures thereto, and as illustrated in Fig. 3, of the drawings the width of the body portion of the fastener, indicated by the lines F—F is greater than the thickness thereof, thereby providing a construction of staple fastener having the necessary strength, while at the same time requiring only one half the amount of material to manufacture the same that is required for the 60 manufacture of similar fasteners formed out of round wire.

The main body portion A, of the staple fastener has bent from both ends thereof at about an angle of ninety-five degrees the duplicate point-shanks B, that are adapted to enter the box side and the cover that is to be secured thereto by the fastener. The outer extremities of the point-shanks B, are provided at both sides of the longitudinal center 70 of the fastener with the point bevels E, the outer side edges C, of which bevels taper at an angle of about forty-five degrees to the entering point D, of the fastener. The point bevels E, are made uniformly on the point 75 extremities of both of the shanks B, and by reason of being formed at both sides of the longitudinal center of the fastener such bevels form at their inner meeting edges the central point ridge G, that is disposed in 80 alignment with the longitudinal center of the fastener and also tapers to the point D, and the said point bevels E, are cut or formed on an angle of about ninety degrees from the central point ridge G, to the outer side edges C, 85 that taper into the sharp points D.

The specific construction of points described, provide the fasteners with points having knife edges G and C, which together with the point bevels forming these knife edges 90 form points of a half diamond shape that will cut their way into the wood of the cover of the box or package irrespective of the run of the grain without a splitting of the wood. It will be further noted that the specific construction of the point extremities of the point-shanks provides means whereby the said points will be forced inward at a sharper 100 angle to the main body portion A, as the same

are driven into the wood, which is clearly illustrated in Fig. 6, of the drawings, and this is due to the incline or taper of the ridges G, and the taper of the point bevels E, which together exert a tendency to force the points farther inward than can be possibly secured in any other fastener, and thereby secures the covers of the vessels or boxes very firmly in position. Furthermore, the objections to the points of the fasteners twisting out of alignment with the body portion thereof is overcome, inasmuch as the herein described points of the fasteners are duplicate constructions and are made to correspond on both sides of the longitudinal center of the fastener, so that in driving the points in they will drive perfectly parallel, or in other words will not turn or twist out of longitudinal alignment with the body of the fastener, and this feature is of the utmost importance in securing covers to packages.

In manufacturing the herein-described fastener, a single length of wire of the proper size and strength is cut into the proper lengths to form a number of the fasteners as is illustrated in Fig. 4, of the drawings, it being understood that any suitable machine capable of performing the work is used to make the fasteners. By reference to Fig. 4, of the drawings, it will be seen that one point

extremity is shown completed, while the other end shows the imprint of the cutting knives of the machine employed to manufacture the fastener, such machine providing for cutting or shaping two points at one operation, while at the same time substantially severing the fastener and leaving the same cut and ready for bending into the proper shape described.

Having thus described the invention, what is claimed, and desired to be secured by Letters Patent, is—

The herein-described staple fastener for wooden vessels and boxes formed of a single length of wire and comprising a straight body portion having duplicate point-shanks bent from both ends thereof at an angle, said point-shanks being provided at their outer extremities with duplicate point bevels formed at both sides of the longitudinal centers thereof and tapered at the other outer side edges into an entering point, said point bevels meeting at the center of the shanks in a point ridge also tapering to the entering point, substantially as set forth.

In testimony whereof I affix my signature in presence of two witnesses.

FRANK W. RICHEY.
